US0D1112724S

(12) **United States Design Patent** (10) **Patent No.:** **US D1,112,724 S**
(45) **Date of Patent:** **** Feb. 10, 2026**

(54) **PROTECTIVE FACE SHIELD WITH HOOD**

(71) Applicant: **PAULSON MANUFACTURING CORPORATION**, Temecula, CA (US)

(72) Inventor: **Roy Paulson**, Murrieta, CA (US)

(73) Assignee: **Paulson Manufacturing Corporation**, Temecula, CA (US)

(**) Term: **15 Years**

(21) Appl. No.: **29/777,642**

(22) Filed: **Apr. 7, 2021**

(51) LOC (15) Cl. **29-02**

(52) U.S. Cl.

USPC **D29/110**

(57) **CLAIM**

The ornamental design for a protective face shield with hood, as shown and described.

DESCRIPTION

FIG. 1 is a perspective view of the protective face shield with hood according to the invention;

FIG. 2 is a front view thereof;

FIG. 3 is a rear view thereof;

FIG. 4 is a left-side view thereof, the right-side view being a mirror image thereof;

FIG. 5 is a top view thereof; and,

FIG. 6 is a bottom view thereof.

The broken lines shown in the drawings represent portions of the protective face shield with hood that form no part of the claimed design.
